COMBINATION BLADE DISPENSER AND
USED BLADE RECEIVERAngelo Arrighi, Union City, N. J., assignor to
American Safety Razor Corporation, Brooklyn,
N. Y., a corporation of Virginia

Application August 21, 1951, Serial No. 242,897

1 Claim. (Cl. 206—16)

1

This invention relates generally to a container into which used blades may be disposed of and more particularly to the integration therewith of a containing space from which new blades may be dispensed for use in a razor.

The general object of the invention is the provision of an improved arrangement for receiving and storing used razor blades and more particularly single edge razor blades of the type wherein the unsharpened edge is thickened with a reinforcing back.

A more particular object is an improved arrangement whereby used blades can be entered into one part of a razor blade container for storage and disposal and new blades dispensed from another part of said container.

For the attainment of these objects and such other objects as may herein appear or be pointed out, I have illustrated one embodiment of my invention in the drawings wherein:

Fig. 1 is a perspective view of the razor blade container, partly broken away, showing a new blade partially dispensed therefrom and a used blade partially inserted therein;

Fig. 2 is a view of the front end of Fig. 1;

Fig. 3 is a section on line 3—3 of Fig. 2;

Fig. 4 is a view of the rear end of Fig. 1; and

Fig. 5 is an exploded view showing the component parts of the container.

The container is herein disclosed as particularly devised to dispense single edge blades 15 of the standard type whose unsharpened rear edge is thickened by reinforcement 17. The container is comprised of side walls 12, front end wall 13, rear end wall 14, top wall 11 and bottom wall 31. The end walls 13 and 14 are provided with inwardly extending longitudinally aligned ribs 26 and 27 engageable with notches 29 in the side edge of the blades to hold them in vertically stacked relation. The rib 27 has its upper portion 28 of uniform thickness and its lower portion 27' tapered downwardly toward the end wall 14 for a purpose to be hereinafter referred to. In the drawings, the upper portion 28 has its inner edge 28' parallel to the end wall 14 for substantially one-half of its length and has substantially the other half of its length tapered, as shown at 27', and said tapered portion 27' preferably ends at the top of the used blade entrance mouth (to be hereinafter described). Extensions 27² and 27³ extending laterally from each side of rib 27 and tapering laterally into the end wall 14 are also provided for a purpose to be hereinafter referred to. It will be observed that the notches 29 are located adjacent and slightly forwardly of the reinforcement 17.

An exit mouth 18 for this type blade, is provided in the upper portion of forward end wall 13 through which the topmost blade may be ejected. The mouth is enlarged at one end 18' to receive the reinforced back 17 of the blade and at the other end 18² for blade edge protection.

The stack is held elevated against the under surface of top wall 11 by spring 16 to align the topmost blade with mouth 18.

In order to give access to the interior of the container for filling it with blades, rear end wall 14 is shown in the illustrated embodiment as formed independently of the container body, as may be clearly seen in Fig. 5 wherein rear end wall 14 is shown as provided with tongues 23 projecting outwardly therefrom and received in recesses 24 provided in the container side walls. Proper location of the end wall for the complete assembly of the container is assured by the provision of a top ledge 25 which is adapted to abut against the end of top wall 11.

Top wall 11 of the container body is provided with open ended guide slot 19 for the manually reciprocable ejector 20 whose finger 21 is normally positioned to the rear of the reinforcement 17 of the topmost blade.

Rib 40 depending from the undersurface of top 11, extends longitudinally thereof and is located to one side of slot 19 to define with the adjacent side wall 12, a channel in which reinforcement 17 of the topmost blade is received and by which it is guided through mouth 18.

The container incorporates an arrangement whereby used blades may be received and stored therewithin and whose nature will now be described by reference to Figs. 1, 2, and 5. It will be observed that the end wall 14 has its lower edge portion cut away to bevel 50 to provide the slot portion 33 at the right in Fig. 5, whose height is no less than the thickness of reinforce 17 and the slot portion 33' which is cut away to bevel 51 and of a lesser height than portion 33; that the length of the cut away portion 33 is shown in Fig. 1 as approximating but preferably slightly in excess of the depth of the thickened portion 17 of the razor blade; that the length of portion 33' is shown as approximating but preferably slightly in excess of the depth of the unthickened razor blade portion which is to the front of reinforce 17; that the bottom 31 of the casing in Fig. 5 is cut away as shown at 35 for a length at least equal to the depth of the reinforce 17; that rib 27 (Fig. 5) extending forwardly from the rear wall 14 is located slightly to one side of cut away portion 33 and registers with rib 36 (Fig. 2) inside the

bottom of the container body, when assembly is completed.

As a result of the details of construction set forth in the paragraph preceding, the assembly of the rear wall 14 of Fig. 5 with the casing of Fig. 2 will provide a closed chamber which presents at the top of the casing, discharge mouth 18 for new blades and at the bottom of the casing, an entry mouth for the used blades. In the illustrated embodiment, the discharge mouth is shown at the upper end of the front wall and the entry mouth as at the lower end of the rear wall, so that the mouths are located at diagonally opposite top and bottom corners of the casing.

This used blade entry mouth is widened at cutouts 33 and 35 to receive the thickened rear blade reinforce and narrowed at the rear wall cutout 33' to receive the relatively thinner blade portion to the front thereof. The used blade is thus precluded from being entered except as shown in Fig. 1.

The aforementioned rib 36 has its end 36' beveled as shown in Fig. 5, so that a used blade entered into said mouth will engage said bevel and be elevated thereby to the level of the top of rib 36 for reasons to be pointed out.

The spring 16 shown in Fig. 5 has been specially devised to function with both the new blades stacked thereabove and the used blades entered therebeneath through the mouth adjacent the bottom of the casing, as will be more fully set forth.

Spring 16 is shown in Fig. 5 as formed from an elongated strip of spring metal bent upwardly and backwardly intermediate its ends to define a bottom portion 16' and a top portion 16² which extends angularly upwardly and backward from the bend. It will be observed that: the undersurface of this bend 16³ is concavely curved; the angle of bend is shown as acute; the inner end of the bottom portion immediately adjacent the bend 16³, is provided with an upwardly directed depression defined by angularly related walls 16⁴. The spring is made from sheet material and is of a width which approximates and preferably slightly exceeds that of the thickened portion 17 so that the spring can be received in the casing in underlying relation to the thickened portions of the new blades stacked thereon.

The container is assembled and loaded by inserting the spring 16 endwise with the bend 16³ to the rear, into the open end of casing of Fig. 5, and in between the rib 36 and the adjacent end wall 12 with the bottom portion 16' seated on the bottom of the casing and also inserting the ejector 20 into slot 19 of the top wall of the casing; new blades are entered stacked above the spring by depressing its finger 16², whose tension applies an upward pressure to the stack to engage its topmost blade against the undersurface of the top wall. The blades are held registered by engagement of rib 26 on the casing front wall, in the notches 29 on the adjacent ends of the blades. The end wall 14 (Fig. 5) is then entered into and closes the open end of the casing and enters its rib 27 into the notches at the other end of the stack. The adjacent ends of the bottom and rear walls define the entrance mouth for used blades.

Upon reference to Fig. 1 it will be observed that the first used blade 34 is shown as partially entered into the container with its reinforce 17 underlying spring 16 which in turn underlies the reinforces 17 of the new blade stack. In reach-

ing this position, the advancing end of the blade will have engaged with and been elevated by bevel 36' and will have engaged the curved spring surface 16³ and been directed downwardly therein to beneath the spring. Continued advance of the blade 34 from its position of Fig. 1 will be guided and controlled by downward pressure of the spring 16.

Full entry of the used blade 34 and engagement of its advancing notch 29 with rib 26 is assured by cutaway portion 35 (Fig. 5) into which the pushing finger of the operator may enter. The notch 29 will normally engage rib 27. However, if the blade has shifted in its insertion so that the notch 29 is not directly beneath the rib 27 so as to be engaged thereby, the tapered portion 27' will still permit the blade to be elevated and will prevent the blade from otherwise being jammed in the container by abutting the lowermost portion of rib 27 if the rib 27 were not tapered. The tapered extensions 27² and 27³ will facilitate the centering of the used blade 15 as it is being elevated by successive insertions of used blades.

Following used blades are enterable in the same way, however without engaging spring 16 which is now interposed between the new and the used blades. As a result, the pressure applied by spring 16 will be maintained uniform because for every new blade that is dispensed at the top, an old blade will be entered at the bottom. Spring 16 will however be gradually elevated until it engages against the under surface of the casing top wall when the new blades are completely exhausted. The rib 36 and its bevel 36' are important in that they elevate the used blades already entered below the spring, to a level above the entry mouth to thus permit the entry of a succeeding used blade therebelow. In this manner, used blades can be entered successively through the entrance mouth therefor without interference by the previously entered and lowermost used blade below the spring.

It will be observed upon reference to Fig. 1 that the weight of the stack of new blades is applied directly to the free end of the upwardly inclined finger portion 16² of spring 16 and that this finger portion will be angled downwardly thereby into closer adjacency to the base portion 16 to tension the spring. This angling of the finger is facilitated by the curved portion 16³ and the angularly related walls 16⁴ which define the upwardly directed depression in front thereof. This resulting spring tension is applied upwardly to the new blades and also downwardly to the used blades therebeneath.

I claim:

A combination dispenser and used blade receiver for blades having end notches, said container having side, end, bottom, and top walls, a used blade entrance mouth in an end wall adjacent said bottom wall and a new blade exit mouth in an end wall adjacent said top wall, a locating rib extending inwardly from each of said end walls to enter the notches in said blades for location, the rib on the end wall which has said used blade entrance mouth having a portion of uniform depth for substantially one-half of its length and having a portion tapered inwardly toward said end wall, said uniform depth portion being the upper portion of said rib and said tapered portion being the lower portion of said rib, and said tapered portion terminating above said used blade entrance mouth, spring means 75 for elevating new blades to the level of said exit

mouth and an access opening in the top wall for ejecting a topmost blade through said exit mouth.
